UNITED STATES PATENT OFFICE.

HUGH H. WHITEHEAD, OF PALMETTO, FLORIDA, ASSIGNOR OF ONE-HALF TO RICHARD H. WHITEHEAD, OF PALMETTO, FLORIDA.

INTERNAL-COMBUSTION ENGINE.

No. 919,103.

Specification of Letters Patent. Patented April 20, 1909.

Application filed July 3, 1908. Serial No. 441,851.

To all whom it may concern:

Be it known that I, HUGH H. WHITEHEAD, a citizen of the United States, residing at Palmetto, in the county of Manatee and State of Florida, have invented a new and useful Internal-Combustion Engine, of which the following is a specification.

This invention relates to internal combustion engines of the multiple cylinder type.

10 The invention consists in general of a pair of cylinders, the axes of which are in angular relation to each other and which are open to each other at one end, pistons in the cylinders, a single crank shaft, and a special form of connecting rod to actuate the crank shaft.

The invention further consists in certain novel arrangements of details and combinations of parts hereinafter fully described, 20 illustrated in the accompanying drawings, and specifically set forth in the claims.

In the accompanying drawings like characters of reference indicate like parts in the several views, and Figure 1 is a sectional view of an engine constructed in accordance with this invention, the parts being shown as at the beginning of the forward stroke. Fig. 2 is a similar view showing the parts at the end of the forward stroke.

30 The numeral 10 indicates the base of the engine and in suitable bearings 11 formed on that base is a crank shaft 12. A pair of cylinders 13 are mounted on the base 10 with their axes angularly disposed to each other in such manner that the plane passing through the axes will also pass through the axis of the crank shaft. These cylinders converge at the top and open into each other as at 14 to form a common combustion chamber. A piston 15 is held to reciprocate in each of the cylinders 13 and this piston is so arranged that the back end is adjacent and inclined to a plane perpendicular to the axis of the piston as at 16. It 40 is preferred that this incline be sufficient so that when the pistons are in the position indicated in Fig. 1, the upper edge of each of the pistons will be nearly in contact with the back head of the cylinder in which it moves; this back head being common to both cylinders, while the lower edge will be nearly in contact with the plane of intersection of the two cylinders. Each of the pistons 15 is provided with a cross bar 17

50 at the front end in which is formed a hemi-

spherical recess 18 arranged to receive the spherical head 19 of a piston rod 20. This spherical head is held within the recess by means of a plate 21 securely bolted to the cross-bar 17 in the manner common to ball 60 and socket joints so that a universal joint connection is provided between the said rods 20 and the respective pistons.

The crank shaft 12 is provided as at 22 with suitable cranks each having a spheroidal 65 journal 23. The crank ends of the rod 20 are provided with spheroidal bearings arranged to fit the spheroidal journals 23 of the cranks so that the angle of the journal axis and the axis of the rod may vary as the 70 journal rotates from one point of its path to another. It will be observed from an inspection of the drawings that the engine shaft passes through the lower ends of the two cylinders with the crank located within 75 the said lower ends of the cylinders and the lower end of one of the cylinders 13 is closed as at 24 to form an air tight crank casing into which opens a supply pipe 25 provided with a suitable valve and in communication 80 with a source of hydro-carbon. This valve is not deemed necessary here to be shown as the same forms no part of the present invention. Leading from the closed end 24 of the cylinder 13 to the combustion chamber 14 is 85 a pipe 26 forming the supply pipe for the combustion chamber 14.

At 27 is shown an exhaust from the combustion chamber and at 28 is a spark plug of any suitable or preferred form. Oil cups 29 90 and drain cocks 30 are also provided for the purposes common to such articles.

The entire cylinders are jacketed as at 31 and the pipe 26 which establishes communication between the lower end of one cylinder 95 and the upper end of the same cylinder, extends through this jacket for the two cylinders as is clearly shown in Fig. 1 of the drawings, the pipe being in this manner completely inclosed. Upon one end of the crank shaft 100 12 is mounted a fly-wheel 32 provided with a starting handle 33 normally held retracted into the body of the fly-wheel 32 by means of a spring 34.

It will be observed from an inspection of 105 the position of the inlet and exhaust ports that the pistons themselves act as the valves in this engine. In order to understand the operation of the engine let it be supposed that the parts are in the position shown in 110

Fig. 1 and that a charge of the hydro-carbon explosive mixture has been drawn into the crank case 24. The handle 33 is drawn out and the engine cranked in the usual manner. This causes the piston to descend and compresses the mixture in the crank case 24. As soon as the upper end of the inlet pipe 26 is passed by the upper end of the piston 15, the compressed gases rush out through that pipe forcing the burned or spent gases out through the port 27. The next half revolution of the crank again causes the parts to assume the position shown in Fig. 1. This compresses the mixture contained in the combustion chamber 14 and when the compression has been fully accomplished the spark plug is actuated by any suitable means not deemed necessary here to be shown, and the charge fired. The pistons again descend in the cylinders and the cycle of operation is repeated, it being obvious that after the first explosion no further cranking is necessary.

The engine as thus constructed is seen to be of simple form and one in which a much smaller amount of room is consumed than where the two cylinders are located in parallel relation. This construction will be found useful in motor cars, power boats and the like, where the room is greatly constricted above the crank shaft.

It is obvious that minor changes may be made in the form and proportions of the device without departing from the material principles thereof. It is not therefore, desired to confine the invention to the exact form herein shown and described, but it is wished to include all such as properly come within the scope thereof.

Having thus described the invention, what is claimed as new, is:

1. In an internal combustion engine, a pair of diverging cylinders open to each other at

one end, pistons in the cylinders, a crank shaft having its axis in the plane of the axes of the cylinders, rods connecting the pistons and crank shaft, the said shaft extending through the lower ends of the cylinders, an inlet opening into the lower end of one cylinder, and a pipe establishing communication between the upper and lower ends of the said cylinder.

2. In an internal combustion engine, a pair of diverging cylinders open to each other at one end, pistons in the cylinders, a crank shaft having its axis in the plane of the axes of the cylinders, and rods connecting the pistons and crank shaft.

3. In an internal combustion engine, a pair of diverging cylinders, open to each other at one end, pistons in the cylinders, a crank shaft having its axis in the plane of the axes of the cylinders, rods connecting the pistons and crank shaft, the said shaft extending through the lower ends of the cylinders, an inlet opening into the lower end of one cylinder, and a pipe establishing communication between the upper and lower ends of the said cylinder, the said cylinder being jacketed and the said pipe extending through the jacket of the last mentioned cylinder.

4. In an internal combustion engine, a pair of diverging cylinders open to each other at one end, a piston having its end inclined with respect to its axis mounted to reciprocate in each of said cylinders, a crank shaft having its axis in the plane of the axes of the cylinders, and rods connecting the pistons and crank shaft.

In testimony that I claim the foregoing as my own, I have hereto affixed my signature in the presence of two witnesses.

HUGH H. WHITEHEAD.
